CLAIM

(52) **U.S. Cl.** **D8/14.1**

The ornamental design for a portion of a cover for an adhesive dispensing gun, as shown and described.

(58) **Field of Classification Search** D8/14.1;

DESCRIPTION

219/230; 222/146.5, 153.14, 323, 473; 239/1,

FIG. 1 is a front perspective view of a portion of a cover for an adhesive dispensing gun according to the invention.

239/106, 112, 328, 323, 527, 528, 583

FIG. 2 is a front view of the portion of a cover for an adhesive dispensing gun according to the invention.

See application file for complete search history.

FIG. 3 is a left side view of the portion of a cover for an adhesive dispensing gun according to the invention.

(56) **References Cited**

FIG. 4 is a top view of the portion of a cover for an adhesive dispensing gun according to the invention; and,
